UNITED STATES PATENT OFFICE.

JULIUS KINDERVATER, OF RICHMOND, VIRGINIA.

FLEXIBLE STAY BOLT.

Application filed June 10, 1926. Serial No. 115,029.

My invention relates to staybolts for steam boilers. In order to permit limited relative movement of the fire box wall and the outer boiler shell, the parts connected by 5 staybolts to prevent substantial relative movement, it has been the practice to make use of staybolt structures providing for a very limited relative movement of the parts. Such devices have been open to the objection 10 that relative movement longitudinally of the connected parts subjected the fire box wall, and the inner end of the bolt rigidly attached thereto, to injurious distorting strains. My invention has for its object 15 the provision of a staybolt structure which will be free from the objections referred to and which will permit the necessary degree of relative movement of the connected parts. The invention comprises a double ball-joint 20 structure and includes a sleeve member having a ball-joint engagement with the boiler shell, or a sleeve mounted thereon, and a ball-joint engagement with the outer end of the staybolt proper. The two ball-joint structures 25 thus provided are located preferably contiguous to each other at or near the boiler shell and provide the required degree of relative movement of the parts. The hollow sleeve member permits the application 30 therethrough of an anvil member to the outer end of the staybolt while the inner end is being riveted to the fire box wall.

The improvement claimed is hereinafter fully set forth.

In the accompanying drawings: Figure 35 1 is a view, partly in side elevation and partly in vertical section, of a staybolt structure embodying my invention; Fig. 2, a view, in vertical section, of the upper portion of a 40 staybolt structure embodying a modified form of my invention; Fig. 3, a view, in side elevation, of the intermediate sleeve forming a part of my invention; and, Fig. 4, a view, similar to Fig. 1, showing a further modi- 45 fied form of the invention.

In the practice of my invention, referring descriptively to the specific embodiment thereof which is herein exemplified, the staybolt structure, includes a bolt 5 permanently 50 attached at its inner end to a fire box wall 6, the inner end of the bolt 5 being threaded as at 7 for engagement with a threaded opening in the wall 6 and having its inner end upset or riveted as at 8, when the bolt has 55 been placed in position in the fire box wall.

The outer end of the bolt 5 has an en-

larged spherical portion 9 for cooperation with a socket 10 provided in the lower end of a sleeve member 11 having its upper end spherically formed on its outer surface as at 60 12. The spherically formed portion 12 of the sleeve 11 is adapted to engage a complementary formed seat 13 provided on the inner surface of the upper end of a sleeve member 14 having threaded engagement at 65 15 with the boiler shell 16, so that a ball and socket joint is formed at the point of engagement of the sleeve member 11 with the sleeve member 14.

It will be seen that with the construction 70 described a double ball and socket joint formation is provided by the ball 9 in the socket 10, and by the spherical portion 12 in the seat 13. The relatively greater flexibility achieved by the double ball and socket 75 formation thus provided overcomes any tendency for the occurrence of distorting strains at the point of connection of the inner end of the staybolt 5 with the fire box wall 6.

The opening or passageway 17 through the 80 sleeve member 11 is utilized in the mounting of the structure in a boiler, in that an anvil part or member may be inserted through the opening 17 to bear against the outer end of the bolt 5 to support the bolt during 85 the application of a riveting operation to the lower end thereof. In addition, a slot 18 in the upper end of the bolt 5 provides for the rotation of the bolt through the use of a suitable tool for turning the bolt to 90 position in the threaded opening in the fire box wall 6 in which the lower end of the bolt is received.

The sleeve member 14, which is shown in 95 Fig. 1 of the drawings, provides for the location of the upper ball and socket structure outside of the boiler shell 6, as will be seen, and a cap member 19 engages the outer end of the sleeve 14 and covers the included parts.

In Fig. 3 is shown the form of the sleeve member 11 before the assembly of the parts and in which the inner portion of the sleeve member has a cylindrical opening 20 therein. When, however, assembly has taken place, the rim portion 21 of the sleeve member 11 is pressed inwardly, as is shown in Fig. 1, to provide a socket formation which will cooperate with the ball-shaped outer end portion 9 of the bolt 5.

In the modification shown in Fig. 2 of the drawings, a sleeve member 22 is shown which

has a spherically formed upper end portion 23 adapted to engage directly with the edges of an opening 24 formed in the boiler shell to provide a spherical seat in which the 5 rounded sleeve portion 23 may have universal movement. The sleeve member 22 is relatively shorter than the sleeve member 11 shown in Fig. 1 since it is formed for direct engagement and cooperation with the edges 10 of the opening 24 formed in the boiler shell itself. Preferably the diameter of the opening 24 in the boiler shell is such that the lower portion of the sleeve 22 will pass through the opening 24, thereby facilitating 15 the operation of mounting or demounting the parts in position in the boiler structure. The restricted size of the opening 24, as compared with the size of the opening in which the sleeve 14 is received, tends to leave a 20 stronger boiler shell structure since less of the material making up the wall is removed in forming the opening. It will also be seen that the utilization of the small sized opening makes it possible to use lighter material 25 for the wall structure, as such a lighter walled structure with its smaller opening will have approximately the same strength as that of a thicker walled structure with larger openings.

30 A protecting sleeve member 25 is welded or otherwise attached to the exterior surface of the boiler shell 6 in enclosing relation to the opening 24 formed therein while a cap member 26 is applied to the sleeve member 25 to cover the enclosed parts.

In the modification shown in Fig. 4 of the drawings, is an embodiment of the invention in which another form of sleeve member 27 is used. In this form, the sleeve member is 40 provided with a spherical portion 28, similar to that shown in Fig. 2, which cooperates directly with the edges of the opening 29 formed in the boiler shell 30. The sleeve 27, however, is provided with a relatively larger 45 bore 31. This construction is less expensive to produce than that shown in Figs. 1 and 2, in that the opening 31 may be formed by a single operation. In order to reinforce the bearing portion 28 of the sleeve 27, a plug 50 member 32 is inserted in the upper end of the sleeve member 27 and has threaded engagement therewith as at 33. The construction is otherwise similar to that already described.

55 I claim as my invention and desire to secure by Letters Patent:

1. In a boiler staybolt structure, a bolt adapted to be attached at its inner end to the fire box wall and having a spherical 60 outer end, and a sleeve member having an exterior bearing surface at its outer end spherically formed to provide a ball and socket connection with the boiler shell, said sleeve member having a socket at its other

end in which is fitted the spherical outer 65 end of the bolt.

2. In a boiler staybolt structure, a bolt adapted to be attached at its inner end to the fire box wall and having a spherical outer end, a member for connecting the bolt 70 to the boiler shell, said connecting member having a ball formation at one end and a socket formation at the other end, and the boiler shell being provided with an opening 75 formed to provide a seat for the spherical outer end of the connecting member, the socket portion of the connecting member being adapted to receive said spherical outer end of the bolt.

3. In a boiler staybolt structure, a bolt 80 having threaded engagement at its inner end with the fire box wall and having a spherical outer end, a sleeve member having a socket formation at its lower end in which to receive the outer spherical end of the bolt, said sleeve member having a ball-shaped upper end, the boiler shell being provided with an opening formed to provide a seat for the spherical outer end of the sleeve, and the outer end of the bolt being provided with a slot to receive a tool 85 passed through the hollow sleeve for turning the bolt to seat the same in the fire box wall.

4. In a boiler staybolt structure, a bolt 90 having threaded engagement at its inner end with the fire box wall and having a spherical outer end, a sleeve member having a socket formation at its lower end in which to receive the outer spherical end of the bolt, said sleeve member having a ball-shaped upper end, the boiler shell being provided with an opening formed to provide a seat for the spherical outer end of the sleeve, the outer end of the bolt being provided with a slot to receive a tool, said opening in the boiler shell having a restricted diameter to permit the lower end 100 of the sleeve to pass therethrough with a minimum of clearance, a sleeve attached to the exterior surface of the boiler shell in enclosing relation to the opening, and a cap member adapted to close the outer end of the sleeve.

5. In a boiler staybolt structure, a bolt 110 attached at its inner end to the fire box wall and having a spherical outer end, a sleeve member having a socket formation at its lower end in which to receive the outer spherical end of the bolt, said sleeve member having a ball-shaped upper end, the boiler shell being provided with an opening 115 formed to provide a seat for the spherical outer end of the sleeve, and a plug member for closing the outer end of the sleeve member.

6. In a boiler staybolt structure, a bolt 120 attached at its inner end to the fire box wall

and having a spherical outer end, a sleeve member having a socket formation at its lower end in which to receive the outer spherical end of the bolt, said sleeve member having a ball-shaped upper end, the boiler shell being provided with an opening formed to provide a seat for the spheri-

cal outer end of the sleeve, a plug member having screw-threaded relation with the outer end of the sleeve, a sleeve member attached to the exterior surface of the boiler shell in enclosing relation to the opening, and a cap member for said sleeve member.

10 JULIUS KINDERVATER.
